UNITARY SANDING AND POLISHING
MACHINE

Edwin W. Daum, Louisville, Ky.

Application January 29, 1936, Serial No. 61,326

3 Claims. (Cl. 51—170)

In finishing welded and other rough surface portions of automobiles, it is customary, in automobile paint and repair shops, garages and factories, to cut down the surface initially by means of an electrically driven sanding machine. After this operation lacquer is usually sprayed on the sanded surface and the latter thereafter polished by means of an electrically driven polishing machine. The sanding machine operates at a relatively high speed say 4,000 R. P. M. while the polishing machine operates at a lower speed usually in the neighborhood of 1,000 R. P. M. Except for these necessarily different operating speeds, both machines largely have common requirements. They must be portable, i. e. easily carried by hand; hence lightness in weight is highly desirable. They must also be capable of use around surfaces which are irregular in shape and of restricted access; hence they should be small and compact. Furthermore they are apt to be handled by unskilled as well as skilled operators with varying degrees of care; consequently sturdiness is an important factor.

The principal object of the present invention is to provide in a single unit a machine which is capable of operation at a high speed as a sander and at a lower speed as a polisher and to accomplish such objective without sacrificing any of the requirements for such machines.

Another object is to provide a machine which may be easily and quickly changed from either character to the other.

A further object is to provide a simple, compact and sturdy arrangement of gears connecting the driving motor to the working spindle and, in combination therewith, a simple and easily operated gear shift for changing from one speed to another.

A further object is to provide a gearing which is self-locking in either of its different speed positions.

A still further object is to provide a structure of this character which may be easily assembled or disassembled.

A still further object is to provide a gear housing in which all operating shafts are contained in the same plane and thereby facilitate the machining of the shaft supporting parts of the housing to the end of reducing its cost of manufacture.

The invention is illustrated in the accompanying drawing wherein:

Figure 1 is a side elevation of a device constructed in accordance with my invention;

Figure 2 is a top plan view thereof;

Figure 3 is a vertical longitudinal section taken through line 3—3 of Figure 2;

Figure 4 is a transverse section taken along lines 4—4 of Figure 3.

Figure 5 is a vertical longitudinal section taken through line 5—5 of Figure 2; and

Figure 6 is a perspective of the gear shift rod.

In carrying out the invention a driving motor 1 of any suitable character is provided. A handle 2 is fixedly secured to one end of the motor, this handle preferably carrying a motor control switch 3 which is resiliently urged outwardly in any well known manner to the "motor off" position. The motor drive shaft projects from the opposite end of the motor through an opening in a cross member or plate 4 which is interposed between the motor and the gear housing 5. The plate 4 and housing 5 may be detachably secured to the motor in any suitable manner as by the bolts 6. A handle 7 is detachably secured to one side of the gear housing and adapted for securing to the other side thereof so as to condition the machine for use by either right or left handed operators.

The plate 4 and housing 5 cooperate to provide a support for a pair of spaced parallel shafts 8 and 9 located on opposite sides of the motor shaft. These shafts preferably are arranged in the longitudinal or axial plane of the motor shaft because the corresponding shaft-receiving openings and recesses in the plate and housing can then be machined or bored easier, quicker and with less skilled labor thus keeping the manufacturing cost at a minimum.

The motor shaft drives the shaft 8 through a spiral pinion 10 and spiral gear 11 both of which are fixedly secured to their respective shafts. The shaft 8, in turn, is arranged to drive the shaft 9, at a low speed, through spiral driving gear 12 and driven gear 13 and, at a high speed, through spiral driving gear 12a and driven gear 13a. The spiral driven gears 13 and 13a are fixedly mounted in spaced relation on the shaft 9 while the spiral driving gears 12 and 12a are slidably mounted on the shaft 8 for movement from the low speed driving position through a neutral or non-driving position to the high speed driving position. The spiral driving gears 12 and 12a may be constructed and arranged in any suitable manner but, as shown, the high speed gear 12a is simply fitted over and keyed to a peripheral portion of the low speed gear 12 thus making a composite unit of the two gears.

In connection with the high and low speed gearing above described it may be pointed out that the gears may be made of any desired design. The use of spiral gears is preferred because they operate quietly with a minimum of vibration and because they are easier to move into meshing relation than most if not all of the other available types of gears. While the spiral gears used may be arranged to exert their end thrust effect in one direction or another, I prefer to arrange the low speed spiral gears 12 and 13 so that their end thrust effect is directed away from the high speed position and to arrange the high speed gears 12a

and 13a so that their end thrust is directed away from the low speed position. In other words, with the arrangement illustrated in Figure 5, the end thrust of the low speed gears is directed to the right while that of the high speed gears in Figure 3 is directed to the left. In this manner the low and high speed gears tend to lock themselves in their respective operating positions.

In order to shift the slideable gears from one position to another the slideable driving gear 12 is provided with a peripheral groove to receive a fork 14 which is fixedly secured to one end of a gear shift rod 15. The latter shaft passes successively through, and is supported by, a partition 15 in the gear housing and the end wall of the housing. This shaft terminates, on the outside of the housing, in a detachable knob 16.

With self-locking gears in the high and low speed positions, it will be understood that the gears will normally remain in such positions except perhaps under unusual circumstances. As a further safeguard, however, additional locking means are provided for the high and low speed positions which means are also made effective to lock the device in an intermediate or neutral position. Accordingly the gear shift rod 15 is provided with three recesses 17 which are spaced from left to right at intervals corresponding to the high speed, neutral and low speed positions 30 of the gears. The rod is resiliently held, in any of these positions, by suitable means such as a spring pressed ball lock 18 of any desirable type.

The two speed shaft 9 carries, at one end, a bevel pinion 19 which is held in fixed meshing or driving relation with a bevel gear 20 on the work spindle 21. The spindle is located slightly beyond one end of the shaft 9 and is positioned at a right angle to, but in the plane of, the shaft 9. It extends from a partition in the housing outwardly through a cap 22 which is detachably secured to the housing. The cap is made large enough to permit the removal of the spindle and its bevel gear as a unit through the opening which is normally closed by the cap. The outer end of 45 the spindle removably carries a sanding device 23 of the usual form. For polishing operation this head may be covered by a polishing cloth 24 of the usual character.

It will be readily seen that the foregoing machine has the dual characters of both a sanding and a polishing machine and that it may be converted from one to the other simply by appropriately shifting the gears and affixing or detaching the polishing cloth. Furthermore such characters are attained without sacrificing any of the qualities desirable in machines of this general character such as sturdiness, compactness, and portability. In this latter connection it may be pointed out that the machine described has been 55 constructed with a weight of ten and one-half pounds which, as will be obvious, renders it exceptionally easy to carry and manipulate. Besides the self-locking feature, it has the further advantage of being exceptionally easy to assemble and disassemble. For example, upon removal of the bolts 6, the plate 4 and housing 5 may be separated from the motor and from each other thus permitting the removal of shafts 8 and 9 with their respective gears, and rendering the removal of the gear shift rod subject only to the detachment of its knob. As previously pointed out, the spindle can be removed simply

upon removal of the bolts or other means by which the cap is held to the housing.

While the structure and operation of this device has been explained in connection with its use as a sanding and polishing machine it will be understood that no limitation is intended thereby as it may be used generally for the drilling of holes and various other purposes.

Having described my invention, I claim:—

1. A gear unit of the class described comprising a gear housing having a spindle, said housing being adapted for securement to a motor having a drive shaft, gearing within the housing for connecting the shaft to the spindle, said gearing including a pair of low and high speed gears which are laterally shiftable between low and high speed positions, the low speed shiftable gear cooperating in the low speed position with another gear to produce end thrust which is directed away from the high speed position and the high speed shiftable gear cooperating in the high speed position with another gear to produce end thrust which is directed away from the low speed position, and manually controlled means for shifting the said gears from either position to the other. 25

2. A gear unit of the class described comprising a gear housing having a spindle, said housing being adapted for securement to a motor having a drive shaft, a pair of intermediate shafts rotatably mounted within said housing, one intermediate shaft being connected to the drive shaft and the other to the spindle, a pair of low and high speed spiral gears mounted on each intermediate shaft, one pair of said gears being shiftable laterally along its shaft from one position 35 wherein the low speed gears of each pair mesh with each other to another position wherein the high speed gears of each pair mesh with each other, the low and high speed gears being relatively reversely spiraled so as to produce reverse 40 end thrust effects which respectively tend to maintain the low and high speed gears in their respective low and high speed positions, and manually controlled means for shifting the gears from either position to the other. 45

3. A portable machine of the class described comprising a motor having a drive shaft, a gear housing having a work spindle adjacent one end and being open at its other end which is removably securable to the drive end of said motor, 50 a member extending across the open end of said housing and having an opening through which the drive shaft of the motor projects into the gear housing when motor and housing are secured, said cross member being removable from the housing when motor and housing are unsecured, a pair of intermediate shafts extending axially within the housing and being rotatably mounted at one end on said cross member and at the other end on a housing wall, one shaft being geared to the spindle and the other to the motor drive shaft, interengageable shiftable multi-speed gearing mounted on said intermediate shafts, and an axially movable rod extending axially through the spindle end of the housing 55 into engagement with the shiftable gearing, said rod being manually operable to shift the gearing, said rod and intermediate shafts with the shiftable gears attached being axially insertable into and removable from the housing 60 through its open end when the cross member is removed therefrom. 70
